UNITED STATES PATENT OFFICE.

JOHN KANE, OF PHILADELPHIA, PENNSYLVANIA.

DESIGN FOR A MEMBER FOR FUSIBLE COUPLINGS FOR FIRE-EXTINGUISHING NOZZLES.

SPECIFICATION forming part of Design No. 32,534, dated April 17, 1900.

Application filed February 14, 1900. Serial No. 5,223. Term of patent 14 years.

To all whom it may concern:

Be it known that I, JOHN KANE, a citizen of the United States, residing in the city and county of Philadelphia, in the State of Pennsylvania, have invented and produced a new and useful Design for a Member for Fusible Couplings for Fire-Extinguishing Nozzles, of which the following is a specification, reference being had to the accompanying drawings, forming part hereof.

In the drawings,

Figure 1 is a view in face elevation of a coupling member showing my new design.

Figure 2 is a view of the same in edge elevation.

As shown in the drawings, the leading or material feature of my design consists of a tongue *a*, projecting from the body of the member *A* outwardly and downwardly, the base of said tongue being located at a point

intermediate of the length of the member *A* and just below an opening *b* of plan corresponding to the outline of the tongue.

One face of the member is, however, below the region occupied by said tongue and opening, transversely ridged.

Having thus described my invention, what I claim, and desire to secure by Letters Patent, is—

The design for a member for fusible couplings for fire extinguishing nozzles, as herein shown and described.

In testimony that I claim the foregoing as my invention I have hereunto signed my name this 5th day of February, A. D. 1900.

JOHN KANE.

In presence of—

F. NORMAN DIXON,
THOS. K. LANCASTER.
